UNITED STATES PATENT OFFICE

155,392

DESIGN FOR A BOTTLE CARRIER

Paul F. Danielson, San Marino, Calif.

Application June 26, 1948, Serial No. 147,230

Term of patent 14 years

(Cl. D58—4)

To all whom it may concern:

Be it known that I, Paul F. Danielson, a citizen of the United States, residing at San Marino, in the county of Los Angeles and State of California, have invented a new, original, and ornamental Design for a Bottle Carrier, of which the following is a specification, reference being had to the accompanying drawing, forming part thereof.

In the drawing:

Fig. 1 is a perspective view of a Bottle Carrier, showing my new design; and

Fig. 2 is a top plan view thereof.

I claim:

The ornamental design for a bottle carrier, as shown.

PAUL F. DANIELSON.
